UNITED STATES PATENT OFFICE.

GEORGE HENRY LIPE, OF CHINA GROVE, NORTH CAROLINA.

CAR-COUPING.

SPECIFICATION forming part of Letters Patent No. 340,447, dated April 20, 1856.

Application filed December 4, 1855. Serial No. 184,675. (No model.)

To all whom it may concern:

Be it known that I, GEORGE HENRY LIPE, of China Grove, in the county of Rowan, and State of North Carolina, have invented a new 5 and Improved Car-Coupling, of which the following is a full, clear, and exact description.

My invention relates to car-couplings of that class in which the coupling-pin is supported by an apertured sliding plate, which is forced 10 back by the approaching car to allow the coupling pin to fall to coupling position; and the invention has for its special object to provide for easily uncoupling cars jammed or crowded together when they stop.

15 The invention consists in certain novel features of construction and combinations of parts of the car-coupling, all as hereinafter fully set forth.

Reference is to be had to the accompanying 20 drawings, forming part of this specification, in which similar letters of reference indicate corresponding parts in all the figures.

Figure 1 is a perspective view of the front 25 part of one of my improved car-couplings, partly broken away and in section. Fig. 2 is a longitudinal sectional elevation thereof, showing the coupling-pin raised in position for coupling as the cars come together. Fig. 3 is a detail longitudinal sectional elevation showing 30 the coupling-pin-holding slide forced in and the coupling-pin raised and held as when uncoupling cars which are jammed tightly together. Fig. 4 is a plan view, with the draw-head and coupling-pin in section, on the line 35 $x-x$, Fig. 2, and shows the coupling-pin raised prior to coupling with an approaching car. Fig. 5 is a like view with the coupling-pin down, as when the cars are coupled; and Fig. 6 is a cross-sectional elevation taken on the 40 line $y-y$, Fig. 5.

The draw-head A, which may be fitted to the car in any approved way, has a link-receiving socket, a , which preferably is broad and quite narrow vertically, to support the 45 coupling-link B about in horizontal position, as in Fig. 2.

The coupling-pin C is formed with a broadened rectangularly-shaped portion, c , between its upper and lower round parts, $c' c''$, respectively, and the pin is fitted in a vertical 50 hole in the draw-head, the upper part, d , of which hole is shaped to fit the part c of the pin,

and has front and rear vertical central grooves at $d' d''$, Figs. 2 and 3, to give space for the expansion of the spiral spring D, which is placed on the upper round part, c' , of the pin, and acts between the upper shoulders of the part c of the pin and a cap, E, held at the top of the draw-head, to force the coupling-pin C downward, as hereinafter more fully explained. 60 The lower part, d'' , of the coupling-pin hole is formed partly above and partly below the link-socket a , whereby stop-shoulders are formed at d'' , to limit the descent of the pin. (See Fig. 6.)

65 In a horizontal recess of the draw-head, above the link socket a , is fitted to slide the coupling-pin trip-plate F, which is enlarged at its outer end to form shoulders f , which strike shoulders f' of the trip-plate recess when the plate is forced inward by the draw-head of an approaching car, and springs G G, held on stems 70 $g g$, projecting from the back end of the trip-plate, force the plate forward, so it normally projects in front of the draw-head, as in Figs. 75 1, 2, and 4. The outward movement of the trip-plate is limited by the contact of the back wall of the rear part, h of a $\perp$ -shaped slot or hole, H, made in the trip plate with the pin C, and through which part h the lower round 80 part, c'' , only of the coupling-pin may pass, while the rectangular part c of the pin will pass freely through the forward widened part, h' , of the trip-plate hole H. The part c of the coupling-pin is long enough to hold the trip-plate back when the pin is down. (See Figs. 85 5 and 6.)

In a cavity in the head of the trip-plate F is fitted to slide a latch-plate, I, and a spring, J, in front of the latch-plate normally forces it 90 backward toward the coupling-pin C. The plate I preferably is held in place squarely across the draw-head by screws or pins K K, which are passed into the trip-plate F and through slots $k k$ of the plate I, said screws 95 K K limiting the backward movement of the plate I, the rear edge of which is notched, as at i , allowing the side parts, $i' i''$, at the back of the plate at each side, to be forced by the spring J beneath the lower end or shoulders 100 of the part c of the raised pin, while the lower round part of the pin enters the notch i , as shown in Fig. 3.

The cap E is fitted on a plate or neck, L,

which is shown made separate from the draw-head, but may be cast on it, and said neck L has two diametrically-opposite angular slots, $l\ l$, which have vertical portions opening at the top of the neck and horizontal parts at the sides of the neck. A pin, l' , passed through one side of the cap E, and a set-screw, l'' , passed through the opposite side of the cap, may be passed down through the vertical parts of the slots $l\ l$, and the cap then will be turned to carry the ends of the pin and screw $l'\ l''$ into the horizontal parts of the slots $l\ l$, and the screw l'' then will be tightened to hold the cap E in place, so it will hold the spring D under compression between it and the rectangular part c of the coupling-pin.

By removing the cap E the coupling-pin C, and also the trip-plate F and its springs G, may be removed at any time for repair or renewal.

The operation is as follows: When the coupling-pin C is pulled up against the tension of the spring D, the springs G instantly will force the trip-plate F forward, so that the pin C will rest, by its rectangular part c , on the top of the plate F behind the part h' of the slot H, as in Fig. 4. As the cars come together, the trip-plate F will be forced inward, and as the spring D holds the lower shoulders of the part c of the pin snugly to the top of the part of the trip-plate at the sides of the slot h , and as the latch-plate I stands above this plane when the trip-plate is pushed in by the advancing car, the latch-plate will strike the lower end of the part c of the coupling-pin, and will be pushed forward by the pin and against the tension of the spring J until the part c of the pin coincides with the part h' of the slot in the trip-plate, whereupon the spring D acts instantly to force the coupling-pin down through the link B of the advancing car which had just entered the draw-head, as in Fig. 5.

To uncouple the cars when they are not jammed together, the pin C of one draw-head will be pulled up, and the springs G will carry the trip-plate forward, when the part c of the pin passes above the trip-plate on which the raised pin will be held by the spring D, as in Fig. 2.

Should the cars stop jammed or crowded together, the trip-plates F of the couplings will be forced fully inward, and the latch-plates I will rest with their rear edges against the fronts of the parts c of the coupling-pins, and will then be pressed outward against the tension of their springs J, and so that when one of the coupling-pins is pulled upward the plate I of that coupling will be forced by its spring J beneath the rectangular part c of the raised coupling-pin, and will hold up the pin when it is released from the hand and is forced downward by the spring D, and as shown in Fig. 3. Should the jammed cars now be drawn apart the trip-plate F through which the raised

pin C passes will be forced forward, and as 65 the forward edges of the lower shoulders of the part c of the pin will not pass from the tops of the rear parts, $i\ i'$, of the latch-plate I as it is carried forward by the trip-plate until the shoulders $h\ h'$ at the back of the part 70 h' of the pin-hole pass under the part c of the pin, it is obvious that the pin will be held up in the part h of the hole H, and the link may be drawn from the draw-head, leaving the coupling set ready for automatically coupling 75 onto the link of another car as occasion may require.

The cap E may be held to the neck L, or a projection on the draw-head, or to a flat top of the draw-head by means of screws or pins in 80 any approved way; but the fastening by means of the J-shaped slots $l\ l$ and pin and screw l' l'' is at present preferred.

I extend the link-socket a behind the coupling-pin hole for a distance a very little more 85 than the thickness of the end of the coupling-link, whereby heavy strains on the link or pin will be avoided as the cars start.

Having thus fully described my invention, I claim as new and desire to secure by Letters 90 Patent—

1. In a car-coupling, the combination, with the draw-head, a coupling-pin held vertically therein, and a spring-pressed trip-plate, F, of a spring-pressed latch-plate, I, held to slide 95 in plate F, and notched at i at its rear edge and slotted at h , and the limiting-screws K, passed through slots k , substantially as herein shown and described, and for the purposes set forth.

2. In car-couplings, the combination of the draw-head having a link-socket, a , the coupling-pin C, having a rectangular part, c , and fitted in a vertical hole in the draw-head, having stop-shoulders at d , a trip-plate, F, springs 105 forcing said plate forward beyond the face of the draw-head, and said plate being slotted vertically at H, to support the pin and let it fall, a spring-pressed latch-plate, I, fitted to the trip-plate F, and adapted to operate with 110 the coupling-pin substantially as specified, a spring, D, on the pin C, above the part c , and a removable cap, E, secured to the draw-head above the spring, substantially as herein set forth.

3. In car-couplings, the combination, with the draw-head socketed at a , a trip-plate, as at F, and a coupling-pin C, and spring D, adapted to operate with the trip-plate F, substantially as specified, of a neck or projection, 120 L, on the draw-head, provided with opposite angular slots $l\ l$, and a cap, E, provided with a pin, l' , and screw l'' , adapted to the slots l , substantially as herein set forth.

GEORGE HENRY LIPE.
